United States Patent Office

Des. 203,665
Patented Feb. 8, 1966

203,665

VEHICLE

Wayne K. Cherry, Rochester, Jack R. Finegan, Detroit, and Bernard N. Smith, Oak Park, Mich., assignors to General Motors Corporation, Detroit, Mich., a corporation of Delaware

Filed Nov. 12, 1964, Ser. No. 82,558

Term of patent 7 years

(Cl. D14—3)

Fig. 1

Fig. 2

Fig. 3

Fig. 4

FIGURE 1 is a side elevational view of a vehicle showing our new design;

FIGURE 2 is a top plan view;

FIGURE 3 is a front elevational view; and

FIGURE 4 is a rear elevational view.

The dominant features of our design reside in the full line portions of the drawings.

We claim:

The ornamental design for a vehicle, substantially as shown and described.
